UNITED STATES PATENT OFFICE.

GEORGE W. STAFFORD AND ALBERT E. KELMEL, OF PROVIDENCE, RHODE ISLAND, ASSIGNORS TO THE CROMPTON & KNOWLES LOOM WORKS, OF WORCESTER, MASSACHUSETTS.

DOUBLE-ACTION JACQUARD-MACHINE.

SPECIFICATION forming part of Letters Patent No. 625,208, dated May 16, 1899.

Application filed September 3, 1898. Serial No. 690,165. (No model.)

To all whom it may concern:

Be it known that we, GEORGE W. STAFFORD and ALBERT E. KELMEL, citizens of the United States, residing at Providence, in the county 5 of Providence and State of Rhode Island, have invented certain new and useful Improvements in Double-Action Jacquard-Machines, of which the following is a specification, reference being had therein to the accompanying drawings.

The invention relates more particularly to what are known as "double-action" or "double-acting" jacquard-machines. In certain forms of machines of this class there is employed for each neck and tail cord a double hook or hooked upright, and the machine has two moving griffs working alternately and both intended to engage with the said double hook or hooked upright, but not both at the same time, the one griff ascending while the other is descending for one pick, and vice versa for the next pick, and so on. In consequence of the fact that the double upright has a plurality of griff-hooks, one for engagement with each moving griff, it follows that when one griff is descending, carrying with it an upright which previously was raised, but which should occupy a lowered position in the next shed formation, the disengaged hook on said upright projects into the path of movement of the ascending griff, and hence the latter will engage with the said hook of the descending upright unless such engagement is provided against, and by arresting the descent of such upright and carrying it back into an upper position will make thereby a false indication and cause a mispick. With the objects in view of preventing undesired engagement of a descending upright by the ascending griff and at the same time obviating the necessity of making a second or extra beat of the card cylinder or prism for the same purpose we have invented certain mechanism, which is presented in our applications for 45 United States Letters Patent, filed June 15, 1898, Serial No. 683,512, and September 3, 1898, Serial Nos. 690,163 and 690,164. The mode heretofore adopted in practice of providing against such undesired engagement of the descending upright by the ascending

griff—namely, by occasioning a second or extra beat of the card cylinder or prism—is seriously disadvantageous. When it is undertaken to prevent such engagement by causing such second or extra beat of the card cylinder or prism to take place at the time when the two moving griffs are passing each other in order to present again to the needles the same card which was last presented thereto, a slowing down of the operation of the loom 55 below the speed that otherwise would be attainable is necessitated, inasmuch as such additional movement of the card cylinder or prism renders it necessary to occasion two complete beats or movements of the cylinder 60 or prism for each pick of the loom. For instance, if it were desired to run a loom at the rate of one hundred and fifty picks per minute the card cylinder or prism would be required to make three hundred beats against 70 the needles per minute. By obviating the necessity of making the second or extra beat of the card cylinder or prism for the purpose of preventing improper engagement of the ascending griff with the descending upright and 75 by providing devices to press back the descending uprights out of the reach of the ascending griff, as fully disclosed in our applications aforesaid, we are enabled to run a loom having a double-action jacquard-machine applied thereto at a higher rate of speed than we heretofore have known to be possible. In our said applications we have presented and claimed certain press-back wires or needles and devices for operating the same 80 in the proper relations with the uprights and moving griffs.

Our present invention consists in an improved construction of the press-back devices and in certain provisions for preventing the hook of a descending upright from becoming accidentally disengaged from the griff with which it is moving.

The invention will be described first with reference to the accompanying drawings, after which the distinguishing characteristics thereof will be particularly pointed out and distinctly defined in the claims at the close of this specification.

Figure 1 of the drawings shows in side ele- 100

vation certain portions of a double-action jacquard-machine having our invention applied thereto, only such old parts being shown as are necessary in order to make clear the 5 nature and mode of operation of the invention. Fig. 2 is a view, mainly in transverse vertical section, showing certain of the parts which are represented in Fig. 1. Fig. 3 is a partial plan.

10 The framing and certain fixed parts which are applied thereto are designated 11 in Figs. 1 and 3, the usual bottom board being designated 2, the double hooks or uprights being designated 3 3, the usual needles coöoperating therewith being designated 4 4, the springs which are applied to the said needles being designated 5 5, and the usual card cylinder or prism being designated 6. The two moving griff-frames are designated 7 and 8, respectively, the blades applied thereto being designated, respectively, 71 and 81 and being arranged in alternating succession, as shown. The two griff-frames 7 and 8 in practice are mounted and actuated in usual manner and 25 through suitable power connections (not necessary to be shown or described herein) and in operation are caused to move simultaneously in opposite directions with respect to each other. The card cylinder or prism 6 in 30 practice will be supported and operated by devices of usual character and construction, (not herein shown,) and thereby will be caused to make one beat for each shed formation, this usually corresponding with one pick of 35 the loom to which the jacquard-machine is applied. The uprights 3 3 are double, as shown, each limb of each of such uprights having a hook, as 31, for engagement with the actuating-griff. One limb of each up- 40 right is designed for coöperation with a griff-blade 71, and the other limb thereof is designed for coöperation with the adjacent griff-blade 81, one of such griff-blades being 45 designed to be uplifted for one shed formation and the other thereof being designed to be uplifted for the succeeding shed formation, and so on in regular alternation.

12 12 designate the blades of a stationary griff such as sometimes is employed—that is 50 to say, in full open-shed jacquard-machines—when it is desired that an upraised upright shall remain in its elevated position for several picks in succession without being caused to descend meanwhile.

55 32 32 designate hooks that are formed on the uprights 3 3 for engagement with the stationary griff-blades 12 12.

The devices which have been described thus far are common to preëxisting jacquard-ma- 60 chines.

With the foregoing devices we combine means whereby as each of the moving griffs in turn descends the disengaged hooks of the uprights which are engaged and descending 65 therewith are pressed back, so that the said hooks thereof shall be out of the path of the ascending griff. Thereby we prevent the as-

cending griff from picking up a descending upright and raising it at a time when it should be lowered into a depressed position. We 70 use wires which are arranged to engage with the respective limbs of the uprights 3 3 and are moved transversely with relation to the griffs at the proper moment in the working of the jacquard-machine, so as to press the disengaged hooks on the said uprights out of the path of the ascending griff-blades. The said wires or their equivalents may be variously constructed, arranged, and applied. We have shown them herein as constituting a set 80 of supplemental needles, the same being designated 13 13 and having eyes or the equivalent thereof where they engage with the limbs of the uprights 3 3, as at 131 131. When these wires are moved toward the right in 85 the drawings, they press the limbs of the uprights to the right also, thereby carrying laterally clear of the ascending griff-blades those hooks 31 31 which are not in engagement with either the ascending griff-blades or the 90 descending griff-blades.

The press-back wires or needles 13 13 are mounted in a movable carrier, herein shown as consisting of cross-bars 33 33, to which the opposite ends of the wires or needles 13 13 are 95 applied, supporting-arms 34 34, by which the said cross-bars are upheld, and slide-rods 35 35, to which the supporting-arms 34 34 are attached. With the carrier for the press-back wires is combined means for reciprocating the said carrier horizontally in proper timing with reference to the movements of the two moving griffs, whereby each time the said moving griffs pass each other the carrier and press-back wires are operated to bear the 100 uprights laterally in order to move the hooks of the disengaged descending uprights laterally clear of the blades of the ascending griff and thereby prevent the engagement of such hooks with the said blades. Preferably 110 we arrange for operating the carrier from one of the moving griffs or a part connected and moving in unison therewith. Thus we have shown in the drawings a cam in engagement with a pin or roller, one of the said parts being 115 connected to move with one of the moving griffs and the other being connected with the carrier. In the present embodiment of the invention the cam herein designated 36 is attached to the slide-rod 9 of the griff-frame 120 7, while the roller which is engaged by the said cam, the same being designated 37 herein, is mounted on a pin 38, which is attached to a slide-rod 35.

361 is a spring surrounding the slide-rod 35 125 between the collar to which pin 38 is applied and one of the bearings for said slide-rod 35. The cam 36 is shaped as shown to occasion a complete reciprocation of the said carrier in each complete vertical movement of the 130 cam up or down. Thereby each time the moving griffs pass each other at an intermediate point in their vertical traverse the carrier, with the press-back wires mounted there-

- in, is moved toward the right, so as to carry the disengaged hooks of the uprights out of the path of movement of the ascending griff-blades.
- 5 Each engagement of the cam and roller (this engagement occurring each time the two moving griffs are about to pass each other) occasions a movement of the carrier and press-back wires to the right in the drawings.
- 10 This operates to carry toward the right, also clear of the ascending griff-blades, all the hooks which are not in engagement with moving griff-blades. Those limbs having the hooks thereof engaged with such griff-blades
- 15 will ordinarily bend under the pressure which is exerted against them by the press-back wires or needles, and it is not intended that the hooks of such limbs should become dislodged from the griff-blades on which they are seated. However, in order to guard against the liability of such dislodging we combine with the press-back wires or needles and the uprights springs, which are interposed between the said wires or needles and
- 20 uprights, and which springs are intended to yield under the pressure of the press-back wires or needles and thereby relieve the strain at the hooks, which would tend to dislodge the latter from the griff-blades. The best ar-
- 25 rangement of the said springs which we have yet contrived is illustrated in the drawings, in which latter the springs themselves are designated 134 134. They are each in the form of a narrow elongated **U** and are mounted with their free extremities extending downward, as shown. The said springs are hung upon cross-rods 135 135, supported by side bars 136 136, made fast to the carrier for the press-back wires or needles, or the said springs
- 30 may conveniently be hung or supported in any suitable manner. The two ends of each spring are introduced, together with the upper end of one limb of an upright, into one of the elongated eyes 137 of one of the wires or
- 35 needles 13. The expansion of the spring within the said elongated eye holds the said limb pressed up against one end of the said eye. When the carrier, and with it the said wire or needle 13, is moved in manner as de-
- 40 scribed above toward the right, the pressure that is transmitted from the wire or needle through the spring 134 to the limb of the upright bears the said limb to the right also, so as to tend to move the said limb sufficiently
- 45 to bear its hook 31 out of the way of the griff-blade which is adjacent thereto. Should, however, the said hook 31 be in engagement at such time with the said griff-blade and moving in unison therewith, the said spring
- 50 134 will yield and become compressed under the resistance which the limb of the upright offers to being moved laterally, and thus the strain exerted against the said limb will be relieved, so that the said hook will not be

forced off the griff-blade. The wires or needles 13 13 are formed in the present embodiment of our invention of flat metal strips, each punched with a number of elongated eyes 137 137. The ends of said wires or needles are sprung into holes prepared therefor 70 in the cross-bars 33 33 of the carrier.

We do not claim, broadly, herein the carrier for the press-back wires or needles, since the same is made the subject of claim in our application for United States Letters Patent, 75 filed September 3, 1898, Serial No. 690,163; nor do we claim the specific devices for actuating the carrier, since the same is made the subject of claim in our application for United States Letters Patent filed on said date, Serial 80 No. 690,164.

We claim as our invention—

1. The combination with the oppositely-moving griffs, the uprights, and the press-back devices to prevent engagement of a descending upright with an ascending griff, of springs interposed between said press-back devices and the uprights to yield and thereby obviate accidental disengagement of an upright from a griff-blade onto which it is 90 hooked, substantially as described.

2. The combination with the oppositely-moving griffs, the uprights, the press-back wires or needles, and actuating devices for such wires or needles, of springs interposed 95 between the wires or needles and the uprights to yield and thereby obviate accidental disengagement of an upright from a griff-blade onto which it is hooked, substantially as described.

3. The combination with the oppositely-moving griffs, the uprights, the press-back wires or needles having elongated eyes receiving the limbs of said uprights, and actuating devices for such wires or needles, of 105 the springs also entered into said elongated eyes and operating to yield and thereby obviate accidental disengagement of an upright from a griff-blade onto which it is hooked, substantially as described.

4. The combination with the oppositely-moving griffs, the uprights, the press-back wires or needles having elongated eyes receiving the limbs of such uprights, and actuating devices for such wires or needles, of 115 the **U**-shaped springs having the extremities thereof also entered into said elongated eyes and operating to yield and thereby obviate accidental disengagement of an upright from a griff-blade onto which it is hooked, sub- 120 stantially as described.

In testimony whereof we affix our signatures in presence of two witnesses.

GEORGE W. STAFFORD.
ALBERT E. KELMEL.
